UNITED STATES PATENT OFFICE.

RUDOLPH BECKER, OF ROSELLE PARK, NEW JERSEY, ASSIGNOR TO THE SINGER
MANUFACTURING COMPANY, A CORPORATION OF NEW JERSEY.

MACHINE FOR STITCHING SWEATBANDS IN HATS.

Application filed September 11, 1918. Serial No. 253,573.

To all whom it may concern:

Be it known that I, RUDOLPH BECKER, a citizen of the United States, residing at Roselle Park, in the county of Union and State of New Jersey, have invented certain new and useful Improvements in Machines for Stitching Sweatbands in Hats, of which the following is a specification, reference being had therein to the accompanying drawings.

This invention relates to a machine for sewing sweat bands in hats and it is especially designed to stitch a leather sweatband to a straw or other stiff hat which has been previously provided with a ridge of needle penetrable material at the junction of the brim and crown.

In my copending applications Serial Nos. 217,051 and 217,052, filed February 14, 1918, which have since become patents numbered 1,280,946 and 1,281,123, granted October 8, 1918, are disclosed new and improved methods of stitching sweat-bands in straw-hats in which methods a strip of needle penetrable material is secured in a variety of ways to a hat body with a soft edge or ridge of the strip located at the junction of the brim and crown after which the leather sweat-band is placed in wearing position within the hat and stitched to the soft edge of the strip preferably without the needle penetrating the stiff hat body which being brittle is likely to chip. This application is a continuation in part of the first of the above mentioned applications, Serial No. 217,051.

The present invention aims to provide a new and improved machine for stitching the leather sweat-band to the soft edge of the strip which has been previously anchored to the hat and thus to avoid the slow and expensive hand stitching operation heretofore necessary to secure sweat-bands in straw hats in the neat and smart fashion demanded by high class trade.

It aims to provide a work supporting and feeding mechanism into and from which the work is readily introduced and removed, and by which the hat may be held in an inverted position with its brim in a plane in fixed relation, preferably at an inclination, to the path of the needle of the stitch-forming mechanism. It seeks to provide an improved organization and arrangement of

the stitch-forming mechanism, work-sus- 55 taining mechanism, and work-feeding mechanism in which the condition of the stitching may be examined during the progress of the operation on a hat.

Further the invention aims to provide 60 a new and combined work-clamping and feeding mechanism.

Also it aims to provide a machine in which a leather sweat-band can be positioned within a hat in substantially the location it occupies in the finished hat and while being stitched in place not only "drummed" in i. e., given a bell-shaped flare to form a cushion, but also drummed in with such facility that inequalities in the 70 size of the blocked hat may be compensated for by stretching or distributing the fullness of the leather sweat-band about the internal periphery of the crown.

It aims further to insure the stitching of 75 the leather sweat-band to the strip of soft material which has been previously secured to the hat with the edge of the leather substantially flush with the underside of the brim and without the exercise of much attention or care by the operator.

And its comprehensive object, which embraces the previously mentioned objects, is to provide a machine enabling the operator to better her output in numbers and quality, 85 thereby meeting the increased cost and shortage of skilled labor in this line of production.

As embodied in working form, the invention comprises a single thread overseaming 90 mechanism having a reciprocating needle which is moved in a path inclined to the plane of the brim of a hat held in an inverted position by a work-rest which may be lowered from its raised (and normal working) position to facilitate the removal and introduction of work, the hat being gripped by its crown, which depends from the work-rest, and intermittently rotated a stitch-length at a time by a combined clasping 100 and feeding mechanism operated from the main-shaft in the head of the machine.

The invention is illustrated in the accompanying drawings in which Fig. 1 is a perspective view of a modification of the invention. Figs. 2 and 3 are details of the same. Fig. 4 is a perspective view of the preferred form of mechanism, the frame be-

ing shown in dotted lines. Fig. 5 is a perspective view of a plate which may be used in either form of the invention. Figs. 6 and 7 are a front elevation and bottom plan view respectively of a work-rest by which the hat is supported. Fig. 8 is a cross-section through a hat at the junction of the brim and crown showing the manner in which the leather sweat-band is stitched to the edge of a strip of needle penetrable material.

In the form of the invention shown on Sheet 1 of the drawings, the frame of the machine is illustrated in dotted lines and 15 comprises a base 1 from which rises a vertical standard 2 canted at its upper end to form a head 3 closed by a lid 4 which is preferably movable on a hinge 5 for ready access to the mechanism within the frame.

20 Within the head 3 is journaled the main-shaft 6 from which the needle 7, needle-bar 8 and looper 9 are actuated by any suitably mechanism, that shown in the drawings being substantially the same as disclosed in 25 U. S. patents to Grieb, No. 1,206,433, granted November 28, 1916, and Prazak, No. 939,548, granted November 9, 1909 and the mechanism of said patents has been found satisfactory in the illustrated embodiment of the invention. The needle-guard 10, Fig. 3, the sweat-guide 11 and cord-guide 12 may also be the same as disclosed in the above mentioned patents.

The hat H, which has been previously 35 provided with a ridge or fold of needle penetrable material at the junction of the brim and crown in any of the various ways delineated in the above mentioned copending applications, is supported by a work-rest in 40 an inverted position with the underside of its brim in a plane inclined to the path of the needle. The work-rest may be made in a variety of ways, as shown in Fig. 1 consisting of a pair of arms or levers 13 secured at 45 one end to a rod 14, which is suitably journaled in a fixed part of the frame of the machine, and at their opposite ends carrying brim supporting members 15 and 16. The brim supporting member 15 is in the 50 form of a T-shaped plate secured by the screws 17 to the ends of the arms or levers 13 and having a depending concaved flange 18 which is adapted to engage the hat externally at the junction of its brim and 55 crown. The brim supporting members 16 are preferably in the form of fingers or bell-cranks hinged on the pins 19 to the before mentioned arms or levers 13 their upper surfaces 20 being co-planar with the top of 60 the plate 15 and their opposed sides 21 being adapted to yieldingly grip the crown of the hat under the action of the coiled springs 22 connecting each finger with a relatively fixed part of the machine such as the plate 65 15. A link 23 connecting the tail ends of

the bellcranks or fingers 16 compels the fingers to move an equal distance and in opposite directions whenever either of them is displaced, thus tending to center the hat at all times relative to the path of the 70 needle which it will be noted is substantially in a vertical plane bisecting the brim supporting plate 15. The work-rest, shown in the drawings in its raised and normal working position, is held therein by the latches 75 24 which are of angular form and are pivoted at 25 intermediate their ends to stops 26 limiting the upward movement of the arms or levers 13, the stops 26 being secured in any suitable manner to the frame of the 80 machine. A spring 27 connected to each of the adjacent ends of the latches 24 normally urges their free ends to a position beneath the arms 13 and thereby holds the work-rest in an elevated position. To lower the 85 work-rest for the convenient introduction and removal of work a chain 28 is loosely connected through the slots 28' to each of the adjacent ends of the latches 24 and by pulling down upon the same through a foot-treadle or other suitable device (not shown) the latches 24 may be removed from their supporting position beneath the arms 13. The work-rest in its lowered position is 90 adapted to rest upon a pair of steps 29 adjustably secured as by the screw and slot connection shown at 30 to a fixed part of the frame.

Cooperating with the depending flange 18 of the brim supporting member 15 is a cup-wheel 31 rotatably supported on a stud 32 fixed in the free end of a bracket-arm 33 integral with or secured in any other suitable manner to the lid 4 closing the head 3 of the frame. The cup-wheel 31 is dished in 100 its upper surface as indicated in the drawings to receive the needle-guard 10, sweat-guide 11 and cord-guide 12 which are supported by the stud 32 in a position fixed of course relative to the needle. Between the 105 cylindrical face 34 of the cup-wheel and the concave face of the flange 18 depending from the brim supporting member, the crown of the hat is confined and the hat is prevented from being displaced bodily in 110 the plane of its brim.

It will be readily apparent that if the hat is rotated while its crown is between the cup-wheel 31 and the depending flange 18 of the work-rest, it will be confined and maintained 115 in definite angular relation with respect to the needle-path. Together the members 18 and 31 compel the crown of the hat to maintain a tangential relation with an imaginary plane at an angle, and preferably at an 120 inclination, to the path of the needle.

The mechanism for turning the hat while its brim is supported by the work-rest at an 125 inclination to the path of the needle comprises a pair of gripping plates 34 having 130

a limited articulation at 35 with levers 36 which are pivoted at 37 to bracket-arms 38 which carry springs 39 engaging extensions 40 of the levers 36 to yieldingly urge 5 the gripping plates 34 against the opposite sides of a hat-crown. The bracket-arms 38 are adjustably secured by screw and slot connections 41 to a block 42, shown in detail in Fig. 2, which is hollowed out inside, its 10 internal flat side walls 43 being disposed in planes intersecting each other at right angles. The hollow block 42 is connected to an upright driving shaft 44 by a universal joint consisting of a knuckle 45 pivoted at 15 46 to the vertical shaft 44.

The shaft 44 is suitably fixed to a feed-disk 47 which is intermittently rotated by mechanism like that of the above mentioned patent to Prazak, No. 939,548. The feed-disk 47 has an upwardly extending annular flange 48 on which rests an actuating plate or lever 49 cut away at 50 to loosely embrace the driving shaft 44. At one side of and beneath the plate 49 a pair of blocks 51 25 are pivotally secured by stud-pins 52. These blocks are arranged on opposite sides of the annular flange 48 which they are adapted to grip when swung in a clockwise direction, as viewed in Fig. 1, but which they 30 do not grip when swung in a counter-clockwise direction. A tension-spring 53 is fixed to the plate 49 as indicated at 54 and at its opposite end to a part of the frame. This spring tends to pull the plate back and keep 35 the blocks snug against the rim or flange 48. A dog 55 pivoted at 56 to a fixed arm 57 prevents rotation of the feed-disk in a counter-clockwise direction as viewed in Fig. 1 but permits rotation thereof in the 40 opposite direction being held against the flange 48 by a spring 58 slightly to one side of the line of centers of pivot 56 and the driving shaft 44. The plate 49, which may be termed a floating wrench is operated 45 from an eccentric 59 on the main-shaft 6 through a series of connections including a pitman 60, a bell crank 61, a link 62 adjustably connected to a slotted bellcrank 63, which in turn is linked to a rod 64 universally 50 sally jointed at its opposite ends to the before mentioned bellcrank 63 and plate 49. Preferably, but not necessarily, a buffer-spring 65 is interposed between the top of the knuckle 45 and the hollow block 42.

55 The foregoing description relates to the modification of the invention which is shown in Sheet 1 of the drawings. Now follows a description of the preferred form of the construction which is shown in Sheets 2 and 3 60 of the drawings.

In the preferred form the frame 100 in general outline resembles the previously described modification its base 101 having in addition lateral supporting pins 102 at its opposite sides which are adapted to rest upon

the margins of an opening provided in a table or bench.

Depending from the base 101 is an approximately H-shaped casting 103 whose cross-bar 104 serves to support a portion of the combined hat clasping and feeding mechanism to be hereinafter described. The head 105 of the machine is closed by a lid or cover 106 which is rigidly secured against displacement by the fastening screws 107. The needle and looper of the stitch-forming mechanism may be constructed and operated in any of the variety of well-known ways preferably as disclosed in connection with the modification shown in Sheet 1 of the drawings.

In construction and operation the work-rest is very much like that previously described. It comprises an arm or lever 108 which is fulcrumed at one end by means of a rod 109 in the stationary frame of the machine. Preferably the boss 110 on the end of the arm 108 is fixedly secured to the rod 109 which is loosely mounted at its opposite ends in the frame, provision against endwise displacement being afforded by the collars 111 suitably secured to the rod 109. The arm or lever 108, which extends forwardly toward the front of the machine, is bifurcated, its forks 112 being wing-shaped and provided at their opposite tips with apertured bosses 113 receiving pintles 114 to which pintles are secured by the pins 115 the sleeve portions 116 of brim supporting members 117 having brim engaging portions 118 and crown engaging portions 119. Loosely hinged on the pintles 114 between the sleeve portions 116 and the upper bearing bosses 113 are additional brim supporting members in the form of conical rollers 120 secured by the shouldered stud-screws 121 to hinged arms 122, spacing blocks 123 being interposed between the rollers 120 and the hinged arms 122.

The hinged arms 122 are apertured as indicated at 124 to receive the ends of springs 125 coiled about the screws 126 threaded in the forks 112 with their opposite free ends reacting against the abutments 127. The springs 125 yieldingly urge the rollers 120 in a plane parallel with that occupied by the brim of the hat and toward the path of the needle, such movement being limited by stop-screws 128 threaded into the rearward extensions 129 of the hinged arms 122 and adapted to strike against the forks 112.

The fingers 117 are also yieldingly urged in a plane parallel with that occupied by the brim of the hat when it is being operated upon, the crown of which hat its portions 125 119 engage. For this purpose an anchoring pin 130 depending from and movable with the arm or lever 108 holds one end of a spring 131 whose opposite end is secured to a slide-block 132 confined to a rectilinear 130

movement by the plates 133, screwed as indicated at 134 fast to the arm or lever 108, in the straight groove 135 provided therein. Depending from the slide-block 132 is a pin 5 136 which is connected by links 137 to each of the arms 138 which have split bosses 139 fastened by the screws 140 to the lower ends of the pintles 114. The fingers 117 can approach each other far enough to yieldingly 10 engage the crown of the smallest hat operated upon but their movement toward each other is limited by the arrival of links 137 into alinement with the crank-arms 138. It will be noticed that the upper surfaces of the 15 rollers 120 and of the fingers 117 are in substantially the same plane and support the brim of the hat in a plane at an angle and preferably at an inclination to the path of the needle.

20 As in the previously described modification the work-rest may be lowered from the raised normal working position shown in Fig. 4, in which it is supported by the screw 141 threaded in the latch 142 fulcrumed at 25 143 to the frame of the machine and held in supporting position beneath the arm or lever 108 by means of a spring 144 whose force may be overcome to disengage the latch by means of a treadle connection or knee shift 30 (not shown) connected to a rod 145. When the latch is disengaged the work-rest may be lowered to a position determined by the depth of a slot 146 cut in the frame of the machine.

35 When a hat is positioned on the work-rest in the manner illustrated in dotted lines in Fig. 4 the spring-pressed rollers 120 hold its crown against a cup-wheel 147 which is preferably fashioned like the previously 40 scribed cup-wheel and which is rotatably supported in any suitable manner on the bracket 148 which is non-yieldingly secured to the lid 106 covering the head 105 of the machine. Within the cup-wheel is provided a needle-guard 149 which is fixed against rotation. Directly above the conical rollers 120 is a plate 150 against which the underside of the brim of the hat is held by the rollers when the work-rest is moved from 45 its lower position to its raised and working position. The plate 150 is secured by the screws 151 to a slotted bracket 152 which is adjustably secured by the screw 153 to a lug 154 jutting forwardly from the inclined head 50 105 of the machine frame. The plate 150 is recessed as shown at 155 the recess being almost closed at one side by the stitch-finger 156 and opposed finger 157 each of which is secured by screws to the plate, the stitch-finger 156 being undercut as indicated at 55 156 to guide the edge of the leather sweatband as it passes to the stitch-forming mechanism.

60 In this preferred construction, as in the previously described modification, while the

hat is supported by the brim on the work-rest and the junction of its brim and crown held in substantially intersecting relation with the needle-path by the cooperating rollers 120 and cup-wheel 147 and while also 70 the hat is held at opposite sides of a vertical plane through the path of the needle by the portions 119 of the fingers 117, it is clasped by its crown and intermittently rotated a stitch-length at a time. The combined clasping and feeding mechanism comprises a pair of gripping plates 158 having limited articulation at 159 with bellcrank-levers 160 which are fulcrumed at 161 to a supporting cross-head 162 fixed to a threaded rod 163 whose 80 lower end is connected by a gimbal joint 164 with a rod 165 having a square end 166 slidably mounted in a sleeve 167 which in turn has its lower end connected by a gimbal joint 168 with a driving shaft 169 similar 85 to the driving shaft 44 of the previously described modification. The driving shaft 169 is intermittently rotated in any suitable manner as by the mechanism described previously for rotating the driving shaft 44 90 there being employed in addition a lever 170 and a link 171 having ball and socket connections with the plate or floating wrench 49 and the link 64.

95 In the preferred form of the construction shown in Fig. 4 the gripping plates 158 may be provided with the clips 172 upon which the crown of a hat is adapted to rest to locate the brim of the hat in a plane at right angles to the axis of the rod 163. For positively gripping the crown of the hat between the plates 158 a disk 173 is threaded upon the rod 163 and by turning this plate the free ends 174 of the bellcranks 160 may be depressed and the gripping plates 158 105 moved equally in opposite directions against the sides of an interposed hat crown with as much pressure as is deemed necessary to insure a firm grip on the hat. The bellcranks 160 may also be provided with triangular shaped ears 175 whose sloping sides are adapted to contact with the sector blocks 176 fixedly secured in any suitable manner to the frame 100 of the machine. The triangular plates 175 and sector blocks 176 110 constitute a means for preventing the gripping plates coming together and holding them separated after the work-rest is lowered and the hat removed at the end of a stitching operation, the sliding connection 115 between the square end of the rod 165 and the sleeve 167 permitting the parts to drop until the plates 175 contact with the sector-blocks 176. Also the plates 175 in connection with the blocks 176 hold the gripping 120 plates 158 upright at this time as it is obvious, because of the universal joint 164, without some kind of support they would 125 have a tendency to fall over to one side.

130 Supposing the machine to have been in

operation and a sweat-band to have been stitched within the hat by the needle 7 and looper 9 in any of the various fashions disclosed in the above mentioned copending applications, the operation of the machine is as follows:—The operator puts her hand beneath the work-rest and then disengages the latches 24 or 142 which supports it in raised position after which she lowers the rest into contact with the stops 30 or 146. In this operation the fingers 16 or 117 disengage themselves from the crown of the hat which is held between the gripping plates 34 or 158. Then the gripping plates 34 or 158 are spread apart to facilitate removal of the finished hat and a new hat is introduced therebetween. After this the work-rest is raised and the brim of the hat settled upon the brim supporting members 15—20 or 120—118. In the manual elevation of the work-rest the operator holds the latches 24 or 142 retracted until the raised working position is reached after which she releases the treadle connection 28 or 145 to permit the spring 27 or 144 to move the latches 24 or 142 into supporting position beneath the arms 13 or 108 of the work-rest. In this position of the parts and upon starting up operation of the machine the needle 7 will penetrate the edge or ridge of the strip of soft material which has been previously secured to the hat-body and the needle 7 will also penetrate the leather sweat-band which has been loosely positioned in the crown before the machine is started to operating. The leather sweat-band while being stitched is in the position it occupies in the finished hat. The operator preferably stitches across the meeting edges of the leather sweat-band and subsequently is able to drum the sweat-band in with ease and facility owing to the convenient position occupied by the leather sweat and also owing to the accessibility for manipulation thereof.

It will be noticed that the operator's view of the stitching point is unobstructed and that the character of the work being done may be inspected throughout the progress of an operation upon a hat. It will be noticed also that the thrust of the needle is resisted by the cup-wheel 31 or 147 and that the latter is non-yieldingly supported in a rigid manner from the frame of the machine. Because of the inclination of the needle-path relative to the plane in which the brim of the hat is supported, the thrust of the needle tends to carry the crown of the hat against the cup-wheel and the brim of the hat down upon the brim supporting members 15 or 120. Owing to this organization or arrangement it is not absolutely necessary to employ a member such as the plate 150 but where the material of the hat body tends to cling to the needle it is advantageous to use such a plate to strip the material from the needle and insure against bodily displacement of the brim of the hat upwardly from the plane defined by the top surfaces of the brim supporting members 15—20 or 120—118. It will also be noticed that the slotted bell crank 63 permits regulation of the feeding mechanism to vary the length of stitch and that the adjustment is accessible located at one side of the machine.

It will also be seen that the brim supporting members 15—16 or 120—117 of the work-rest support the hat the opposite sides of whose crown they yieldingly engage during the stitch-by-stitch movement, while the cup-wheel 31 or 147 confines that portion of the hat crown which is immediately adjacent the brim against the flange or side of the brim member 15 or 120. During the stitch-by-stitch movement of the hat its crown is therefore held in substantially tangential relation to an imaginary plane at right angles to the plane defined by the brim supporting surfaces of the work-rest and at an inclination to the path of the needle.

Having thus set forth the nature of the invention, what I claim herein is:—

1. In a machine for sewing sweat-bands in hats, in combination, stitch-forming mechanism including a needle, cooperating members between which a hat crown adjacent the junction of the crown and brim is adapted to be disposed for maintenance relative to the path of the needle, and a combined holding and feeding mechanism acting independently of said members for turning the work a stitch length at a time.
2. In a machine for sewing sweat-bands in hats, in combination, stitch-forming mechanism including a needle cooperating members between which a hat crown adjacent the junction of the crown and brim is adapted to be disposed for maintenance relative to the path of the needle, a work-clamp independent of said members adapted to grip the hat externally, and supporting and actuating mechanism for moving the work-clamp around intermittently a stitch length at a time.
3. In a machine for sewing sweat-bands in hats, in combination, stitch-forming mechanism including a needle, cooperating members between which a hat crown adjacent the junction of the crown and brim is adapted to be disposed for maintenance relative to the path of the needle, a work-clamp adapted to grip the hat externally, supporting and actuating mechanism for moving the work-clamp around intermittently a stitch length at a time, including connections permitting combined rotary and translatory movement of the work-clamp and of a hat gripped thereby with its brim maintained in a predetermined plane.
4. In a machine for sewing sweat-bands in hats, in combination, stitch-forming

mechanism including a needle, cooperating members between which a hat crown adjacent the junction of the crown and brim is adapted to be disposed for maintenance relative to the path of the needle, a work-clamp adapted to grip the hat externally, and supporting and actuating mechanism for moving the work-clamp around intermittently a stitch length at a time including connections 5 permitting combined rotary and translatory movement of the work-clamp in substantially the plane of the hat-brim and also permitting bodily movement of the work-holder in a direction at right angles to the plane 10 of the first mentioned movements.

5. In a machine for sewing sweat-bands in hats, in combination, a needle, means for supporting and actuating the needle in a path inclined to the plane of the brim of the 20 hat, a work rest, a member cooperating therewith to confine the junction of the brim and crown of the hat relative to the path of the needle when the hat is moved, and a combined clamping and feeding mechanism 25 for advancing the work a stitch length at a time, said work rest and member being relatively separable to permit the introduction and removal of a hat.

6. In a machine for sewing sweat-bands 30 in hats, in combination, stitch-forming mechanism including a reciprocatory needle-bar and a needle carried thereby, a work rest arranged below the needle-bar and shaped to engage one side of a hat in an 35 inverted position, a member cooperating with the work rest and confining the hat in its movement relative to the path of the needle, and a combined clamping and feeding mechanism for advancing the work a 40 stitch length at a time, said work rest and member being relatively separable to permit the introduction and removal of a hat.

7. In a machine for sewing sweat-bands in hats, in combination, stitch-forming mechanism 45 including a needle, a work-rest adapted to be supported in a plane inclined to the path of the needle, a member cooperating with the work-rest and adapted to engage a hat-crown adjacent its junction with 50 the brim, said rest and member maintaining the junction of the crown and brim of the hat adjacent the path of the needle during movement of the hat, a work-clamp having plates for gripping the hat externally, 55 arms to which the plates are articulated, a member supporting the arms, means slidably supporting said member, and mechanism for intermittently rotating said last-named means to turn a hat gripped between 60 the plates a stitch length at a time.

8. In a machine for sewing sweat-bands in hats, in combination, stitch-forming mechanism including a needle, a work-rest adapted to be supported in a plane inclined to the 65 path of the needle, a member cooperating

with the work-rest and adapted to engage a hat-crown adjacent its junction with the brim, said rest and member maintaining the junction of the crown and brim of the hat adjacent the path of the needle during movement of the hat, a work-clamp having opposed concave plates, a supporting arm for each of said plates, means for moving said plates in opposite directions, mechanism for intermittently turning said plates, and a 70 universal joint between said mechanism and said means for moving the plates.

9. In a machine for sewing sweat-bands in hats, in combination, stitch-forming mechanism including a needle, a work-rest adapted to be supported in a plane inclined to the path of the needle, a presser-member cooperating with the work-rest and adapted to engage a hat-crown adjacent its junction with the brim, said rest and member maintaining the junction of the crown and brim of the hat adjacent the path of the needle during movement of the hat, a work-clamp having opposed concave plates, a supporting arm for each of said plates, means for moving said plates in opposite directions, mechanism for intermittently turning said plates, and a universal joint between said mechanism and said means for moving the plates, and a 75 sliding connection between the plates and the mechanism.

10. In a machine for sewing sweat-bands in hats, in combination, stitch-forming mechanism including a reciprocatory needle and cooperating looper, a work-rest sustained in a plane inclined to the path of the needle, a member cooperating with the work-rest to confine the junction of the brim and crown of the hat in its movement adjacent the needle-path, said work-rest and member being relatively separable to facilitate introduction and removal of a hat, a work-clamp having movable gripping plates for clasping a hat-crown externally, and mechanism for intermittently turning the work-clamp 100 between stitches including a shaft arranged below and in front of the work-rest and an articulated connection between the shaft and the work-clamp.

11. In a machine for sewing sweat-bands in hats, in combination, stitch-forming mechanism including a reciprocatory needle and cooperating looper, a work-rest sustained in a plane inclined to the path of the needle, a member cooperating with the work-rest to 110 confine the junction of the brim and crown of the hat in its movements adjacent the needle-path, said work-rest and member being relatively separable to facilitate introduction and removal of a hat, a work-clamp having movable gripping plates for clasping a hat-crown externally, and mechanism for intermittently turning the work-clamp 115 including a shaft arranged below and in front of the work-rest, an extensible link univer- 120

sally jointed at one end to said shaft and articulated at its other end to said gripping plates.

12. In a machine for sewing sweat-bands in hats, in combination, stitch-forming mechanism including a needle and cooperating looper, a work-rest supported in a plane inclined to the path of the needle, a member cooperating with the rest to confine the junction of the brim and crown of a hat in its movements adjacent the path of the needle, said work-rest being movable downwardly below said member to facilitate introduction and removal of work, a work-clamp, and means for intermittently turning the work-clamp including connections permitting the work-rest and member to maintain the junction of the brim and crown of a hat adjacent the path of the needle during a succession of stitch-forming cycles.

13. In a machine for sewing sweat-bands in hats, in combination, stitch-forming mechanism, feeding mechanism, and means confining a hat to turn with its brim in a predetermined plane and with the junction of its brim and crown adjacent the path of the stitch-forming mechanism, said means including a work-rest, an arm supporting the work-rest, a fulcrum for said arm in rear of the stitch-forming mechanism, and means for sustaining the arm raised and the work-rest in operative position, said last-named means including a detachable connection.

14. In a machine for sewing sweat-bands in hats, in combination, stitch-forming mechanism, feeding mechanism, and means confining a hat to turn with its brim in a predetermined plane and with the junction of its brim and crown contiguous to the path of the stitch-forming mechanism, said means including a work-rest, a lever supporting the work-rest, a fulcrum for said lever in rear of the stitch-forming mechanism, and means for sustaining the lever raised and the work-rest in operative position, said last-named means including a spring-latch and manual means for releasing the same.

15. In a machine for sewing sweat-bands in hats, in combination, stitch-forming mechanism, feeding mechanism, and means confining a hat to turn with its brim in a predetermined plane and with the junction of its brim and crown adjacent the path of the stitch-forming mechanism, said means including a work-rest, a lever supporting the work-rest, a fulcrum for said lever in rear of the stitch-forming mechanism, means for sustaining the lever raised and the work-rest in operative position, said last-named means including a latch and manual means for releasing the same, and a pair of fingers sustained in a plane with the work-rest affording supplemental support to the hat.

16. In a machine for sewing sweat-bands in hats, in combination, stitch-forming mech-

anism, feeding mechanism, and means confining a hat to turn with its brim in a predetermined plane and with the junction of the brim and crown adjacent the path of the stitch-forming mechanism, said means including a work-rest hinged in rear of the stitch-forming mechanism, and a pair of fingers movable relative to the work-rest in a plane parallel therewith constituting a supplemental rest for the work.

17. In a machine for sewing sweat-bands in hats, in combination, stitch-forming mechanism, feeding mechanism, and means confining a hat to turn with its brim in a predetermined plane and with the junction of its brim and crown adjacent the path of the stitch-forming mechanism, said means including a work-rest, an arm supporting the work-rest, a fulcrum for said arm in rear of the stitch-forming mechanism, means for sustaining the arm raised and the work-rest in operative position, said last-named means including a latch and means for operating the same, and a stop limiting the extent of movement of the arm.

18. In a machine for sewing sweat-bands in hats, in combination, stitch-forming mechanism, feeding mechanism, and means confining a hat to turn with its brim in a predetermined plane and with the junction of the brim and crown adjacent the path of the stitch-forming mechanism, said means including a work-rest hinged in rear of the stitch-forming mechanism, and a pair of fingers simultaneously movable in opposite directions in a plane parallel to the work-rest.

19. In a machine for sewing sweat-bands in hats, in combination, stitch-forming mechanism including a needle, means for supporting and confining a hat to move with its brim in a predetermined plane at an inclination to the needle and including a work-rest and cooperating wheel, a plurality of clamping plates, and means for turning the clamping plates about an axis transverse the plane of the work-rest and inclined to the path of the needle.

20. In a machine for sewing sweat-bands in hats, in combination, stitch-forming mechanism including a needle, means for supporting and confining a hat to move with its brim in a predetermined plane at an inclination to the needle and including a work-rest and cooperating wheel, a plurality of clamping plates, and means for turning the clamping plates about an axis transverse the plane of the work-rest and inclined to the path of the needle and intermediate the plates, said last-named means including an eccentric upon the main-shaft, a linkage actuated thereby comprising a pitman bell-crank and link, and mechanism between the link and clamping plates for converting the throw of the eccentric into an inter-

- mittent one-way rotation of the clamping plates.
21. In a machine for sewing sweat-bands in hats, in combination, stitch-forming mechanism including a rectilinearly movable needle, a work-rest sustained in a plane inclined to the path of the needle and adapted to engage a hat-crown externally, a rotatable member cooperating with the work-rest and adapted to engage the hat-crown internally, a work-clamp adapted to grip a hat-crown externally and means for turning the work-clamp between stitches from below the plane of the work-rest.
- 15 22. In a machine for sewing sweat-bands in hats, in combination, stitch-forming mechanism including a reciprocating needle, mechanism for turning the hat intermittently a stitch-length at a time, a work-rest including a pair of rollers arranged to engage a hat-crown externally, a wheel adapted to engage a hat-crown internally opposite the rollers, said rollers being rotatable about axes which are respectively 20 parallel and are inclined to the path of the needle, and means for relatively shifting the rollers and wheel to facilitate the introduction and removal of the work.
- 25 23. In a machine for sewing sweat-bands in hats, in combination, stitch-forming mechanism including a reciprocating needle, mechanism for turning the hat intermittently a stitch-length at a time, a work-rest having brim and crown-engaging elements, 30 a brim-engaging member, a crown-engaging member, means yieldingly urging together said elements and said crown-engaging member, and means permitting separation of said work-rest and said members 35 for the introduction and removal of work, said brim-engaging member having an overhanging lip for guiding the edge of a sweat-band in its passage to the stitching point.
- 40 24. In a machine for sewing sweat-bands in hats, in combination, stitch-forming mechanism including a reciprocating needle, mechanism for turning the hat intermittently a stitch-length at a time, a work-rest having a pair of rollers hinged thereto for movement in a plane inclined to the path 45 of the needle and also having a pair of fingers hinged thereto for sustaining a hat with its brim in a plane inclined to the path of the needle, a member fixed relative to the 50 rollers above which it is located, a wheel fixed relative to the rollers to one side of which it is located, said work-rest being pivoted to a fixed part of the machine in rear 55 of the stitching point for lowering the rollers and fingers in order to facilitate introduction and removal of the work.
- 60 25. In a machine for sewing sweat-bands in hats, in combination, stitch-forming mechanism including a reciprocating needle, 65 a work-rest for supporting a hat by its brim with that portion of the crown which is adjacent the brim in substantially tangential relation to a plane which is inclined to the path of the needle, said work-rest 70 having relatively movable members arranged behind and in advance of the path of the needle, mechanism for turning the hat in the work-rest intermittently a stitch-length at a time, and means for confining a 75 hat in the work-rest in the tangential relation mentioned during its stitch-by-stitch movement.
26. In a machine for sewing sweat-bands in hats, in combination, stitch-forming 80 mechanism including a reciprocating needle, a work-rest for supporting a hat by its brim with that portion of the crown which is adjacent the brim in substantially tangential relation to an imaginary plane 85 which is inclined to the path of the needle, said work-rest having means arranged behind and adjacent to the needle-path and having a pair of fingers extending in advance of the needle-path adapted to engage 90 opposite sides of the crown of the hat, yielding means for urging said fingers toward each other, mechanism for turning the hat in the work-rest intermittently a 95 stitch length at a time, and means for confining a hat in the work-rest in the tangential relation mentioned during its stitch-by-stitch movement.
27. In a machine for sewing sweat-bands in hats, in combination, stitch-forming 100 mechanism including a reciprocating needle, a work-rest for supporting a hat by its brim with that portion of the crown which is adjacent the brim in substantially tangential relation to an imaginary plane which 105 is inclined to the path of the needle, said work-rest having means arranged behind and adjacent the needle-path and having a pair of fingers extending in advance of the needle-path adapted to engage opposite sides 110 of the crown of the hat, mechanism for turning the hat in the work-rest intermittently a stitch-length at a time, and means for confining a hat in the work-rest in the tangential relation mentioned during its 115 stitch-by-stitch movement.
28. In a machine for sewing sweat-bands in hats, in combination, stitch-forming mechanism including a reciprocating needle, a work-rest for supporting a hat by its brim 120 with that portion of the crown which is adjacent the brim in substantially tangential relation to an imaginary plane which is inclined in the path of the needle, said work-rest having means arranged behind 125 and adjacent the needle-path and having a pair of fingers extending in advance of the needle-path adapted to engage opposite sides of the crown of the hat, a spring for urging said fingers toward each other, 130

means for compelling the fingers to shift equally in opposite directions when either of them is displaced, mechanism for turning the hat in the work-rest intermittently a 5 stitch-length at a time, and means for confining a hat in the work-rest in the tangential relation mentioned during its stitch-by-stitch movement.

29. In a machine for sewing sweat-bands 10 in hats, in combination, stitch-forming mechanism including a reciprocating needle, a work-rest for supporting a hat by its brim with that portion of the crown which is adjacent the brim in substantially tangential 15 relation to an imaginary plane which is inclined to the path of the needle, said work-rest having a pair of rollers arranged on opposite sides of the needle-path and having means extending in advance of the 20 needle-path sustaining the hat at opposite sides of its crown, mechanism for turning the hat in the work-rest intermittently a stitch-length at a time, and means for confining a hat in the work-rest in the tangential 25 relation mentioned during its stitch-by-stitch movement.

30. In a machine for sewing sweat-bands 30 in hats, in combination, stitch-forming mechanism including a reciprocating needle, a work-rest for supporting a hat by its brim with that portion of the crown which is adjacent the brim in substantially tangential relation to an imaginary plane which is inclined to the path of the needle, 35 said work-rest having a pair of rollers hinged thereto on opposite sides of the needle-path and having means extending in advance of the needle-path sustaining the hat at opposite sides of its crown, mechanism 40 for turning the hat in the work-rest intermittently a stitch-length at a time, and means for confining a hat in the work-rest in the tangential relation mentioned during its stitch-by-stitch movement.

45. 31. In a machine for sewing sweat-bands in stiff, oval crowned hats, in combination, 50 stitch-forming mechanism including a needle, a work-rest including oppositely yielding members for supporting a hat by its brim on opposite sides of the stitch-forming mechanism and with that portion of the crown which is adjacent the brim in substantially tangential relation to an 55 imaginary plane at an acute angle to the path of the needle, mechanism acting independently of the work-rest for turning the hat in the work-rest intermittently a stitch-length at a time, and means for confining a hat in the work-rest in the tangential 60 relation mentioned during its stitch-by-stitch movement.

32. In a machine for sewing sweat-bands 65 in hats, in combination, stitch-forming mechanism including a needle, a work-rest for supporting a hat by its brim with that

portion of the crown which is adjacent the brim in substantially tangential relation to an imaginary plane at an angle to the path of the needle, mechanism for turning the hat in the work-rest intermittently a stitch-length at a time, and means for confining a hat in the work-rest in the tangential relation mentioned during its stitch-by-stitch movement, said work-rest being 70 shiftable away from said confining means for the introduction and removal of work without shifting the confining means.

33. In a machine for sewing sweat-bands 75 in hats, in combination, stitch-forming mechanism including a needle, a work-rest for supporting a hat by its brim with that portion of the crown which is adjacent the brim in substantially tangential relation to an imaginary plane at an angle to the path of the needle, said work-rest being 80 hinged to a fixed part of the machine in rear of and substantially at the level of the stitching point so as to permit dropping of the work-rest for introduction and removal of work, mechanism for turning the hat in 85 and relatively to the work-rest intermittently a stitch-length at a time, and means for confining a hat in the work-rest in the tangential relation mentioned during its stitch-by-stitch movement.

34. In a machine for sewing sweat-bands 90 in hats, in combination, stitch-forming mechanism including a needle, a work-rest for supporting a hat by its brim with that portion of the crown which is adjacent the brim in substantially tangential relation to an imaginary plane at an angle to the path of the needle, said work-rest being hinged to a fixed part of the machine in rear and at 95 substantially the elevation of the stitching point for permitting work to be introduced and removed, mechanism for turning the hat in the work-rest intermittently a stitch-length at a time, and means for confining a hat in the work-rest in the tangential relation mentioned during its stitch-by-stitch movement.

35. In a machine for sewing sweat-bands 100 in hats, in combination, stitch-forming mechanism including a needle, a work-rest including depressible work-engaging elements for supporting a hat by its brim with that portion of the crown which is adjacent the brim in substantially tangential relation to an imaginary plane at an acute angle to the path of the needle, mechanism for turning the hat in and relatively to the work-rest intermittently a stitch-length at a time, 105 and a wheel cooperating with the work-rest to maintain the hat in the tangential relation mentioned during its stitch-by-stitch feeding movement.

36. In a machine for sewing sweat-bands 110 in hats, in combination, stitch-forming mechanism including a needle, a work-rest 115

- for supporting a hat by its brim with that portion of the crown which is adjacent the brim in substantially tangential relation to an imaginary plane at an angle to the path of the needle, mechanism for turning the hat in the work-rest intermittently a stitch-length at a time, and means for confining a hat in the work-rest in the tangential relation mentioned during its stitch-by-stitch movement, and means behind the path of the needle and cooperating with the work-rest to confine the brim of the hat against displacement when the needle is being withdrawn from the work.
37. In a machine for sewing sweat-bands in hats, in combination, a stitch-forming mechanism, cooperating members for maintaining the hat crown adjacent the junction of crown and brim in operative relation to the stitch-forming mechanism, means acting independently of said members adapted to grip the hat, and actuating mechanism for moving said means intermittently a stitch length at a time.
38. In a machine for sewing sweat-bands in hats, in combination, a stitch-forming mechanism, a work-rest, means cooperating therewith to confine the junction of the brim and crown of the hat relative to the stitch-forming mechanism when the hat is moved, and a combined holding and feeding mechanism for advancing the work a stitch-length at a time, said work-rest and cooperating means being relatively separable to permit the introduction and removal of a hat.
39. In a machine for sewing sweat-bands in hats, in combination, a stitch-forming mechanism, a work-rest, means cooperating therewith to confine the junction of the brim and crown of the hat relative to the stitch-

forming mechanism when the hat is being moved, and a combined holding and feeding mechanism for advancing the work to the stitch-forming mechanism.

40. In a machine for sewing sweat-bands in hats, in combination, stitch-forming mechanism, feeding mechanism, and means confining a hat to turn with its brim in a predetermined plane relative to the stitch-forming mechanism, said means including a work-rest and a pair of fingers movable relative to the work-rest in a plane substantially parallel therewith and constituting a supplemental rest for the work.

41. In a machine for sewing sweat-bands in hats, in combination, a stitch-forming mechanism, feeding mechanism, and means confining a hat to turn with its brim in a predetermined plane relative to the stitch-forming mechanism, said means including a work-rest and a pair of fingers simultaneously movable in opposite directions in a plane substantially parallel to the work-rest.

42. In a machine for sewing sweat-bands in hats, in combination, stitch-forming mechanism including a needle, a work-rest for supporting a hat by its brim with that portion of the crown which is adjacent the brim substantially tangent to a plane inclined to the path of the needle, said work-rest being shiftable substantially vertically to permit the work to be introduced and removed, mechanism for turning the hat in and relatively to the work-rest, and means for confining the hat in the work-rest in the tangential relation during its movement.

In testimony whereof, I have signed my name to this specification.

RUDOLPH BECKER.
